UNITED STATES PATENT OFFICE.

HJALMAR T. BLOM, OF CHICAGO, ILLINOIS, ASSIGNOR TO SULLIVAN MACHINERY COMPANY, A CORPORATION OF MASSACHUSETTS.

UNLOADING MECHANISM.

Application filed June 20, 1921. Serial No. 478,958.

This invention relates to unloading mechanism for compressors, and more particularly to auxiliary unloading valves employed in connection with the high stages of multi-stage compressors to prevent excessive temperatures in the high stage or stages when the inlet to one of the lower stages is closed by the main unloading device.

The invention has for its object to generally improve devices of this character, and more particularly to provide means controlled by subnormal cylinder pressure for positively opening communication between the end or ends of the cylinder and the atmosphere, thereby insuring the proper venting of the compressor independently of or prior to the development of pressure therein; to provide a single relief valve for the purpose in question adapted to cooperate with both ends of a double acting cylinder; to provide an auxiliary unloading or relief device which will cooperate with the compressor mechanism beyond the discharge valve or valves thereof to divert the discharge from the compressor from the receiver to the atmosphere, thereby avoiding the necessity of pumping against receiver pressure while preventing escape of the latter during the time the compressor is unloaded; and to provide means for insuring the return of the parts of the auxiliary unloader to normal position when the main unloader is operated to load the compressor.

The foregoing and other objects of the invention, together with means whereby the same may be carried into effect, will best be understood from the following description of one form or embodiment thereof illustrated in the accompanying drawings, in which:

Fig. 1 is a side elevation of a two-stage compressor having the invention applied thereto.

Fig. 2 is an enlarged detail vertical section of a portion of the high pressure cylinder, taken substantially on line 2-2 of Fig. 1.

Fig. 3 is a still further enlarged horizontal section, taken substantially on the lines 3-3 of Figs. 1 and 2, of the auxiliary unloader and adjacent portions of the high pressure cylinder.

The invention is herein illustrated as applied to a compressor of the angle-compound type having a horizontal low pressure double acting cylinder 1, a high pressure double

acting vertical cylinder 2, and driving mechanism for the pistons reciprocable in these cylinders whereby the two stages are operated from a single crank shaft 3. The intake to the low pressure cylinder 1 is through an inlet pipe 4 provided with an automatically operated main unloading mechanism 5 such as is commonly used to unload the compressor when the discharge pressure thereof exceeds a predetermined amount. The air or other fluid under partial compression passes from the first stage cylinder 1 through an intercooler 8 to the high stage cylinder 2 and thence, after final compression, through a discharge pipe 6 to the point of utilization or, as herein shown, to a receiver 7.

When the pressure in the receiver or other system supplied by the compressor rises above the predetermined normal operating pressure, the unloading mechanism 5 is operated in a well-known manner to close the inlet 4 to the low pressure cylinder 1 to prevent the intake of air through the inlet and hence the operation of the compressor to force more air into the main or receiver. However, due to leakage or other causes, a certain amount of air will pass this cylinder into the intercooler and will be compressed in the high pressure cylinder 2 from atmospheric pressure, or from below atmospheric pressure, to the maximum pressure in the receiver. This high compression from a low initial pressure results in an objectionably high temperature in the high pressure cylinder, and in order to prevent such an occurrence there is usually provided an auxiliary unloader or relief device which, when the main unloader 5 is operated to unload the compressor by closing the intake 4, thereby causing the pressure in the system to fall below normal, will operate to vent the high pressure cylinder 2 in such a manner as to prevent the compression of such air or other fluid as may find its way thereto. The present invention relates to improvements in devices of the latter character and, in accordance therewith, the following construction and arrangement are preferably employed.

Referring to Figs. 2 and 3, the cylinder 2 is provided with valve chambers 10 containing intake and exhaust valves 11 and 12 respectively, the former controlling communication between the interior of the cylinder

and intake chambers 13 communicating with the conduit 14 leading from the intercooler 8, as is usual in compressors of the type shown. At the discharge side of the discharge valves 12, the valve chambers 10 at the opposite ends of the cylinder are connected by a passage 15 formed in the cylinder 2 and separated by a partition 16 from the main discharge passage 17 which communicates with the pipe 6 leading to the receiver. The passages 15 and 17 communicate respectively with chambers 18 and 19 formed in a casing 20 secured to the side of the cylinder 2. The chamber 19 is closed at its outer end by a head 21 and encloses a valve cage 22 carrying a check valve 23 adapted, in the normal operation of the compressor, to permit flow from the passage 15 and chamber 18 through the chamber 19 to the discharge passage 17, said valve, however, preventing flow in the opposite direction. The check valve 23 is preferably of flat annular form and is normally held seated by a suitable annular spring 24.

The chamber 18 communicates, through a port 25 in an auxiliary casing 26 secured to the casing 20, with a passage 27 in the latter casing, said passage 27 communicating with a chamber or passage 28 formed in the casing 20 and having a port 29 opening to the atmosphere. The port 25 is normally closed by a valve 30 which may be unseated, as hereinafter explained, to open communication between the passage 15 and the atmosphere through the chamber 18, port 25, passage 27, chamber 28, and port 29, the check valve 23 at this time preventing backward flow of fluid from the discharge passage 17 and receiver 7 to the chamber 18.

For the purpose of operating the valve 30 to unseat the same, there is provided a piston 31 operating in a cylinder 32 formed in the auxiliary casing 26, said piston cooperating with the stem 33 of a pilot valve 34 carried by the valve 30 and controlling a port therein. The pilot valve stem 33 is guided in the stem 36 of the valve 30 and is provided with a shoulder 35 adapted to engage the end of the valve stem 36 and unseat the valve 30 after the pilot valve 34 has been unseated to relieve the pressure on said valve 30, thereby facilitating the unseating of the latter. The pilot valve stem 33 extends through the inner head of the cylinder 32 (which is preferably formed with a suitable guide for said stem), is engaged at its outer end by the piston 31, and is provided with a collar 37 between which and said inner cylinder head is interposed a spring 38 tending normally to hold the valves 30 and 34 seated. The cylinder 32 is closed at its outer end by a head 39 having an atmospheric port 40 and is formed adjacent its inner end with a shoulder 41 against which the piston 31 is adapted to seat when said piston is moved inwardly, as hereinafter

explained, in order to prevent leakage past said piston.

The inner end of the cylinder 32 communicates, through passages 42, 43, and 44 formed respectively in the casings 26 and 20 and the wall of the cylinder 2, with a nipple 45 which bridges the cylinder water jacket 46 and communicates with the interior of the cylinder at substantially the longitudinal center of the latter. Seated at the mouth of the passage 42 is a bushing 47 providing a seat for a check valve 48 which is normally seated by a spring 49. The check valve 48 is provided with a stem 50 which extends through the bushing 47 and has its end disposed in the path of movement of the piston 31, whereby said check valve will be held unseated except when said piston is in a position to permit the seating of the valves 30 and 34 by the spring 38.

In operation, when the main unloader 5 is operated to close the intake 4 and unload the compressor, the condition of partial vacuum or subnormal pressure, created in the cylinder 2 behind the piston 51 therein, is communicated through the nipple 45 and passages 44, 43, and 42 to the check valve 48, causing the latter to be unseated and admit said subnormal pressure to the inner end of the cylinder 32. Thereupon the atmospheric pressure admitted to the outer end of the cylinder 32 through the port 40 will cause the piston 31 to move inwardly, unseating the pilot valve 34 and thereafter the valve 30, thereby opening the passage 15 to the atmosphere. The receiver pressure acting through the passage 17 will then hold the check valve 23 firmly seated, and any fluid passing through the high pressure cylinder 2 will be immediately discharged to the atmosphere without substantial compression.

When the compressor is loaded, the condition of subnormal pressure in the cylinder 2 is replaced by one of normal pressure which will be communicated to the inner end of the cylinder 32, thereby causing the piston 31 to move outwardly and permitting the valves 30 and 34 to be seated to close the port 25. In this connection it will be observed that, by reason of the engagement of the valve stem 50 with the piston 31, the check valve 48 will be held open, admitting pressure to the inner end of the cylinder 32 until the piston 31 has been moved outwardly to a sufficient extent to permit the seating of the valve 30, thereby insuring the return of the parts to their normal position, whereupon the valve 48 will be seated by the increasing pressure in the chamber 18 assisted by the spring 49. Thereafter, the pressure in the passage 15 and chamber 18 will be built up until it equals or exceeds that in the passage 17 and receiver 7, whereupon the check valve 23 will open to permit commun-

cation between the passages 15 and 17 and the discharge of the compressed fluid into the receiver 7 in the usual manner.

It will thus be seen that the invention provides an extremely simple mechanism for preventing the development of excessive heat in the high pressure cylinder of a multistage compressor due to high compression of the fluid from an initial subnormal pressure, 10 said mechanism being positive and reliable in its operation and acting, under the influence of subnormal pressure in the compressor cylinder, to disconnect the latter from the usual receiver and permit the same to 15 discharge to the atmosphere, the parts being so constructed and arranged as to insure their return to normal condition and permit the normal operation of the compressor when the main unloading mechanism is operated to 20 load the compressor, or when the conditions within the compressor are otherwise returned to normal.

While I have in this application specifically described one embodiment which my 25 invention may assume in practice, it is to be understood that this form has been chosen for illustrative purposes merely, and that the invention may be otherwise embodied and practiced without departing from its spirit 30 or the scope of the appended claims.

What I claim as new and desire to secure by Letters Patent is:

1. The combination with a compressor, of means for directly controlling compressor cylinder fluid to effect unloading of said compressor, and means responsive to sub-normal pressure within said compressor for operating said unloading means, said unloading means including a plurality of valve elements 40 adapted to be successively actuated and fluid pressure controlled actuating means for said valves.

2. The combination with a compressor cylinder, of means for unloading said cylinder comprising a valve whose opening eliminates compressive action, said valve opening against fluid pressure produced in said cylinder, and means responsive to subnormal pressure in said cylinder for opening said valve.

3. The combination with a compressor cylinder, of means for unloading the same comprising a normally closed valve opening towards the cylinder and upon which compressor discharge pressure exerts a force to maintain the same closed, and means responsive to subnormal pressure within the cylinder for positively moving said valve to open position.

4. The combination with a double acting compressor, of means arranged between the opposite ends of the cylinder and comprising a valve whose opening eliminates compressive action at both ends of said cylinder for unloading the latter, and means responsive

to subnormal pressure in said cylinder for opening said valve.

5. The combination with a compressor having a cylinder, of a relief valve for venting said compressor to the atmosphere, and means responsive to subnormal pressure within said compressor cylinder for opening said relief valve.

6. The combination with a compressor cylinder, of a relief valve for venting both ends 75 of said cylinder to the atmosphere, and means responsive to subnormal pressure within said compressor cylinder for opening said relief valve.

7. The combination with a compressor having a cylinder and means for normally receiving the discharge from said compressor, of means responsive to variations in pressure in said compressor cylinder for diverting 80 said discharge from said receiving means.

8. The combination with a compressor having discharge valves and with means for normally receiving the discharge from said compressor, of means including a valve opening 90 against the discharge pressure responsive to variations in pressure in said compressor at a point short of said discharge valves for diverting said discharge from said receiving 95 means.

9. The combination with a compressor having discharge valves, of means for receiving the discharge through said valves, and means having direct communication with the compressor cylinder and being responsive to variations in pressure in said compressor for opening a separate discharge at a point beyond said discharge valves.

10. The combination with a compressor having a low pressure cylinder, unloading means therefor, a high pressure cylinder, and discharge valves therefor, means for receiving the discharge through said discharge valves when the compressor is loaded, and means having direct communication with the high pressure cylinder and being responsive to variations in pressure therein; upon unloading of said low-pressure cylinder for diverting any discharge at a point beyond said discharge valves from said receiving means.

11. The combination with a compressor having discharge valves and means beyond said discharge valves for normally receiving the discharge from said compressor, of means also beyond said discharge valves controlled by variations in pressure in said compressor for opening an atmospheric discharge for said compressor, said means including a control element having direct communication with the central part of the compressor cylinder.

12. The combination with a compressor having a cylinder, and means for normally receiving the discharge from said compres-

sor, of means for diverting said discharge from said receiving means to the atmosphere, and means responsive to subnormal pressure in said compressor cylinder for operating said diverting means.

13. The combination with a compressor and means for normally receiving the discharge from said compressor, of means for diverting said discharge from said receiving means to the atmosphere, and means responsive to subnormal pressure in said compressor for operating said diverting means against the discharge pressure during existence of the subnormal pressure.

14. The combination with a compressor having cylinders, of a relief valve for venting said compressor to the atmosphere, a cylinder directly communicating with the interior of a compressor cylinder, and a piston 20 ton in said cylinder for operating said valve to cause it to be positively actuated to effect its venting function.

15. The combination with a compressor cylinder, of a relief valve for venting said compressor cylinder to the atmosphere, a cylinder communicable with the interior of the compressor cylinder, a one-way check opening towards the compressor cylinder controlling the communication between the latter and the second mentioned cylinder, and a piston in said second mentioned cylinder for opening said relief valve.

16. The combination with a compressor having a cylinder and a discharge passage, of a chamber communicating with said discharge passage and having a port communicating with the atmosphere, a cylinder having its ends communicating respectively with the atmosphere and with the interior of said compressor cylinder, a valve for controlling said port, and a piston in said cylinder and cooperating with said valve to unseat the same.

17. The combination with a compressor, of a relief valve for venting said compressor to the atmosphere, a pilot valve carried by said relief valve, and means responsive to variations in pressure in said compressor for unseating said pilot valve and for thereafter unseating said relief valve.

18. The combination with a compressor, of a relief valve for venting said compressor to the atmosphere, a pilot valve for said relief valve, a cylinder communicating with the interior of said compressor, and a piston in said cylinder for successively operating said pilot and relief valves.

19. The combination with a compressor, of a relief valve for venting said compressor to the atmosphere, said relief valve having a stem, a pilot valve carried by said relief valve, said pilot valve having a stem passing through the stem of said relief valve and provided with a shoulder adapted to engage said relief valve stem, and means responsive

to variations in pressure within said compressor and cooperating with said pilot valve stem for successively unseating said pilot and relief valves.

20. The combination with a compressor having a discharge valve and means for normally receiving the discharge from said compressor, of unloading means responsive to variations in pressure in said compressor and including a relief device interposed between said discharge valve and receiving means.

21. The combination with a compressor having a discharge valve and means for normally receiving the discharge from said compressor, of unloading means responsive to variations in pressure in said compressor and including a relief device interposed between said discharge valve and receiving means, and a check valve interposed between said relief device and receiving means.

22. The combination with a compressor cylinder having a discharge valve, a passage communicating with said discharge valve, and a separate discharge passage, of a casing having chambers communicating with said passages respectively, a check valve interposed between said chambers, the chamber communicating with the passage from the discharge valve having a port, and a relief valve responsive to variations in pressure in said cylinder for controlling said port.

23. The combination with a compressor having a discharge valve and means for normally receiving the discharge from said compressor, of a relief device interposed between said discharge valve and receiving means, and means responsive to subnormal pressure within said compressor for operating said relief device.

24. The combination with a cylinder of a double acting compressor, of an auxiliary unloader for said compressor comprising a single relief device cooperating to vent simultaneously both ends of said cylinder and responsive to variations in pressure within said cylinder.

25. The combination with a double acting compressor comprising a cylinder, discharge valves at the opposite ends of said cylinder operative to permit discharge of air during normal loaded running, and a passage connecting said valves, of a relief device communicating with said passage and responsive to variations in pressure within said cylinder.

26. The combination with a cylinder of a double acting compressor, of a single relief device cooperating to relieve both ends of said cylinder, and means communicating with said cylinder at a point intermediate the clearance volumes of the cylinder and responsive to variations in pressure therein for operating said relief device.

27. The combination with a double acting compressor comprising a cylinder, discharge valves at the opposite ends of said cylinder, and a passage connecting said discharge valves, of means normally communicating with said passage for receiving the discharge from said compressor, a relief device for said passage means responsive to variations of pressure in said cylinder for operating said relief device, and a check valve interposed between said relief device and said receiving means.

28. The combination with a compressor having a cylinder, of means controlled by variations in pressure within said cylinder for unloading said compressor, and means operated by variations in pressure in said cylinder and controlled by said unloading means for controlling communication between said cylinder and said unloading means.

29. The combination with a compressor having a cylinder, of means responsive to variations in pressure in said cylinder for unloading said compressor, and means for controlling communication between said cylinder and said unloading means, said communication controlling means being responsive to subnormal pressure in said cylinder to open communication between said cylinder and unloading means, and being controlled by said unloading means to maintain said communication when said unloading means is in position to unload said compressor.

30. The combination with a compressor, of a relief valve for venting said compressor to the atmosphere, means responsive to subnormal pressure within said compressor for operating said relief valve, and a check valve controlled by said operating means for controlling communication between said compressor and said operating means.

31. The combination with a compressor, of a relief valve for venting said compressor to the atmosphere, a cylinder communicating with the interior of said compressor, a piston in said cylinder for operating said relief valve, and a check valve for controlling communication between said compressor and cylinder, said check valve being held unseated by said piston when the latter is in position to open said relief valve.

32. The combination with a compressor cylinder, of a relief valve for venting said compressor cylinder to the atmosphere, a cylinder communicable with the interior of the compressor cylinder, a one-way check valve opening towards the compressor cylinder controlling the communication be-

tween the latter and the second mentioned cylinder, and a piston in said second mentioned cylinder for opening said relief valve and also operative in a given position thereof to hold said check valve open.

33. The combination of an air compressor cylinder having a piston movable therein, inlet and discharge valves and a main unloader valve for said cylinder, an auxiliary unloader valve arranged beyond said discharge valves, and means responsive to a vacuum condition in said cylinder proper for opening said auxiliary unloader valve to relieve the work on said piston.

34. The combination of an air compressor cylinder having a piston movable therein, inlet and discharge valves and a main unloader valve for said cylinder, an auxiliary unloader valve beyond said discharge valves, and means controlled by a vacuum condition in said cylinder proper cooperating with said auxiliary unloader valve to move the latter to relieve the work on said piston.

35. A compressor controlling mechanism comprising a valve common to both ends of a compressor cylinder for controlling the load thereon, and means for controlling said common valve adapted to have direct communication with each end of the compressor cylinder, said latter means being actuated by pressure fluctuations in said ends.

36. A compressor unloading mechanism comprising a valve common to both ends of a compressor cylinder for controlling the load thereon, said valve controlling an atmospheric vent, and means for controlling actuation of said valve, having direct communication with each end of the compressor cylinder, and means whereby said latter means is actuated by pressure fluctuations in said ends.

37. A compressor controlling mechanism comprising a valve common to both ends of a compressor cylinder for controlling the load thereon, and means for controlling said common valve adapted to have communication alternately with the cylinder ends.

38. The combination with a double acting compressor, of a common passage through which the fluid discharged from said compressor passes to the receiver, valve means controlling said passage whereby to control the load on said compressor, and means for controlling said valve means adapted to have direct communication with each end of the compressor cylinder.

In testimony whereof I affix my signature.
